UNITED STATES PATENT OFFICE.

FRANCIS MARION RARIDEN, OF WAYNETOWN, ASSIGNOR OF ONE HALF TO
ALFRED R. HEATH, OF COVINGTON, INDIANA.

CAR-COUPING.

SPECIFICATION forming part of Letters Patent No. 377,689, dated February 7, 1888.

Application filed October 13, 1887. Serial No. 252,242. (No model.)

To all whom it may concern:

Be it known that I, FRANCIS MARION RARIDEN, a citizen of the United States of America, residing at Waynetown, in the county of Montgomery and State of Indiana, have invented 5 certain new and useful Improvements in Car-Couplers, of which the following is a specification, reference being had therein to the accompanying drawings.

10 This invention relates to improvements in car-couplers; and it consists in the construction and combination of the parts whereby the cars provided with this invention may be automatically coupled. They may be uncoupled 15 either from the top or sides of the car, and in case of accident they are automatically uncoupled.

In the drawings, Figure 1 is a side elevation of the invention. Fig. 2 is a longitudinal section of the same. Fig. 3 is a horizontal section of the same.

The letters A and B designate the upper and lower halves of the draw-head. The former is provided at the forward end with the opening C and at the rear with the perforation D. It is further provided upon the inner surface with the slot E, which extends from the said opening to near the said perforation D at the rear. The latter of the said halves is provided 25 at the rear of the said draw-head with the raised level F, which extends back under the perforation D in the said upper half. At the rear of the said raised level is a second raised level, G, upon which the upper half, A, of the draw-head rests. To the rear of the raised 30 level G is the head H, the upper surface of which is flush with the top of the half A of the draw-head.

Mounted upon the level F are the two guides 40 I I, which form the channel K between them. Suspended between the said guides upon the pivotal bearings L is the lever L'. The said lever consists of the beveled apron L² and the lever-arm L', which extends to the rear of the 45 said pivotal bearings L, to produce a long stroke for a slight movement of the apron. Attached to the rear of the said lever-arm is a cord, M, which passes over a pulley, N, suspended in the said channel K, and divides into 50 two cords, M, leading around pulleys O and P to the rear ends of the arms R of the cou-

pling-jaws R'. The said jaws R' are mounted in the draw-head just in front of the apron L², and work in and out of perforations in the side of the said head. Passing back between the halves 55 of the draw-head are the arms R. The said arms are pivoted midway between the said halves by means of the pins S S, which pass through perforations provided in the same. As hereinbefore stated, to the rear of these 60 arms are attached the cords M; also, attached to the rear ends of the said arms are the cords T, which pass around the vertical pulleys N, and joined from the one cord T, which passes out at the perforation D in the upper half of 65 the draw-head. To the rear of the said pins S, and seated in the sides of the said guides I I, are spiral springs, which bear against the said arms R and tend to keep the jaws R' closed.

The two halves of the draw-head are secured 70 together by means of the bolts U, which pass through and bind them together. Upon the upper half of the said draw-head is a stopping-bumper, V, and upon the lower half of the said draw-head, to the rear of the said 75 stopping-bumper V, is a starting-bumper, V'. They are placed on either side of two bars passing crosswise of the car and fastened to the sills thereof. In the head H is a slot, H'. Passing through the said slot is a bar, which is at 80 attached to the sills of the car. Play is allowed in all the constructions herein set forth, as the starting and stopping strain is taken up by the spring W. The said spring is secured in a perforation in the rear of the head H by means 85 of the pin W' and to the car, as desired.

The coupling-link X is shaped substantially as shown, with the barbed heads X' adapted to be caught by the jaws R'. The said heads are further supplied with the perforations X², 90 by means of which the said link is secured to a car provided with the ordinary draw-head, when coupling a car provided with this invention, in which case the said link is fastened in the old-style draw-head first.

The front of the draw-head is further provided with the perforations Y, by means of which the ordinary coupling pin and link can be used.

The operation of the invention in coupling 100 is as follows: The link X is placed in the draw-head on one of the meeting cars. The said

cars are then bumped together, driving the free end of the link into the jaws R' of the opposite car, which immediately close upon the same behind the barbs and hold the said link, thus coupling the car. In uncoupling, the operator grasps the cord T and pulls the same. In doing so the cords T are pulled around the pulleys U, and draw the ends of the lever-arms R in opening the jaws R' and uncoupling the cars. The cord T may be carried to the sides or to the top of a car, as desired, and the coupling operated from that point. The lever L' only operates in case of accident, when the cars would fall one on the other, as in going over an embankment. When this takes place, the cars bend in the couplings. With this coupling, when this occurs, the barbed head of the link X is forced up against the apron L² and raises the same. As the apron L² is raised the lever L' turns upon the fulcrum L and bears the rear end down, drawing the cord M over the pulley N and the cords M around the pulleys O and P. This action draws the rear ends of the arms R, to which the cords M are attached, in and opens the jaws R', allowing the end of the said link to escape. As the barbed

head of the link forces up the apron it is forced forward by the beveled face of the said apron and out between the jaws R'.
What I claim is—

In a car-coupling such as described, the combination of coupling-jaws provided with arms pivotally secured in the draw-head of the said coupler, springs bearing against the said arms to the rear of the pivots, a lever fulcrumed in the said draw-head and provided with an apron resting behind the said coupling-jaws and adapted to be raised by the tilting of the coupling-link, and suitable connections between the rear ends of the said lever and of the said arms, substantially as described, whereby when the end of the said lever behind the coupling-jaws is raised the rear end is depressed and the rear ends of the said arms drawn in.

In testimony whereof I affix my signature in presence of two witnesses.

FRANCIS MARION RARIDEN.
